(Cl. D39—1)

To all whom it may concern:

Be it known that I, Samuel J. Mustain, a citizen of the United States of America and resident of Newark, county of Essex, State of New Jersey, whose post office address is 18 North 12th Street, Newark, New Jersey, have invented a new, original, and ornamental Design for Rakes, of which the following is a specification, reference being had to the accompanying drawing, forming a part thereof.

In the accompanying drawing:

I claim:

The ornamental design for a rake, as shown.

SAMUEL J. MUSTAIN.
